UNITED STATES PATENT OFFICE

2,417,349

PUMP SEAL ASSEMBLY

Samuel Gordon Colbaugh, Kilgore, Tex.

Application April 1, 1944, Serial No. 529,219

1 Claim. (Cl. 103—202)

1

The invention relates to a sealing assembly which is particularly adapted for use in pumps of various types.

In pumping liquids, particularly those carrying abrasive materials, a great deal of wear occurs upon the pump liner or working barrel and upon the pump piston or plunger because the parts are reciprocating relative to each other under the pressure of the liquid being pumped.

It is one of the objects of the present invention to provide a resilient surface to be utilized in a pumping operation and which surface may be applied to either the stationary or the moving portion of the pump so as to create a seal which is maintained by the pressure of the liquid being pumped.

Another object of the invention is to provide a resilient sealing member having a plurality of annular resilient corrugations thereon which are adapted to cooperate with another member in maintaining a seal during the pumping action.

A still further object of the invention is to provide a cylindrical sleeve for pump pistons, plungers, liners and barrels which has a plurality of annular projections forming corrugations thereon so as to create a resilient lip structure which is adapted to flex under the pressure of the fluid being pumped so as to maintain a seal.

Another object of the invention is to provide a sealing member for pumps which may be deposited at an inaccessible location so as to maintain a seal during the pumping operation.

Other and further objects of the invention will be readily apparent when the following description is considered in connection with the accompanying drawings wherein:

Fig. 1 is a vertical sectional view of the upper end of a pumping assembly disposed in a well bore to perform a pumping operation.

Fig. 2 is a vertical sectional view which is a continuation of a lower portion of Fig. 1.

Fig. 3 is a side elevation of the assembly of Figs. 1 and 2.

Fig. 4 is a side elevation of a pump plunger particularly adapted for use in a well bore and to which the invention has been applied.

Fig. 5 is a broken sectional view of one of the sealing members as it is used on the pump plunger of Fig. 4.

Fig. 6 is a vertical sectional view through a slush pump used in circulating mud in the rotary method of drilling wherein the pump liner constitutes a resilient member in accordance with the invention.

2

Fig. 7 is a transverse sectional view through the pump liner of Fig. 6.

In Fig. 1 the tubing 2 extends into the well and has a coupling 3 threaded thereto. This coupling supports the upper end of a working barrel 4 which forms a part of the housing 5 to the lower end of which a nipple 6 is connected. A tail pipe 7 extends downwardly into the well any desired distance.

The nipple 6 has a seat 8 therein which is arranged to receive the standing valve assembly 11. This assembly is made up of a spring sleeve 12 having an enlargement 13 thereon arranged to snap into a recess 14 to hold the standing valve in position. A packing cup 15 prevents the entrance of foreign matter in around the latching sleeve.

A cage assembly 17 carries the valve member 18 in order to prevent any back flow from the pumping assembly into the formation so that once the liquid passes the standing valve 18 it is trapped inside of the assembly and is ready to be elevated to the surface.

In order to provide a chamber and prevent a gas lock from occurring in the pumping assembly a standing tube 20 is affixed to the top of the standing valve assembly 11 and this tube projects upwardly a considerable distance as seen in Fig. 1 and carries a second standing valve 21 arranged in a cage 22.

In order to provide a pumping operation a piston or plunger assembly 25 is arranged to be reciprocated by the string of sucker rods 26 which is connected to the pump plunger by a travelling valve cage 27 having the valve member 28 therein. It will be noted as seen in Fig. 1 that when the plunger is in the lowermost position the valves 21 and 28 provide a chamber 29 which is relatively small so that any gas flowing into the pumping assembly with the oil will pass on through the travelling valve 28.

It seems obvious that when the sucker rods are raised the travelling valve 28 will move upwardly creating a suction in the chamber 29 and tending to lift liquid into the pumping assembly by reducing the pressure on the standing valves 18 and 21. In this manner a charge of liquids is drawn into the pump and on the down stroke the valves 18 and 21 close sharply and the liquid in the chamber 3 which is now elongated is forced past the travelling valve 28 as it moves down. In order to provide a seal around the outside of the plunger 25 the working barrel 4 has been provided with a sealing member which is in the form of a sleeve or liner 30.

This liner is made up of a cylindrical body 31 which may have a suitable reinforcing member 32 therein. The inner periphery of the particular sealing member 30 seen in Fig. 1 has a plurality of annular projections in the form of outstanding lips 32 which are arranged to engage the periphery 33 of the plunger or piston 25. It will be noted that these lips are inclined upwardly as seen in Fig. 1 so that the load of liquid inside of the tubing chamber 34 will be exerted on these lips tending to force them against the periphery of the plunger and provide a seal.

This sealing member may be retained in position by the supporting collars 35 spaced above and below the member so as to retain it in the working barrel in a firm position.

It seems obvious that in operation as the plunger 25 reciprocates that a suction will be created in the tube 20 and the chamber 37 around the standing valve. The lips or corrugations 32 will prevent the flow of liquid from the tubing down into this chamber on the upstroke. On the down stroke the pressure in the chambers 29 and 37 will be increased and it will be noted that the lips 32 are inclined upwardly so that if there is excessive pressure from below that there may be a flow of liquid around the liner in an upward direction which would tend to flush out any material which might have settled therein.

It seems obvious that the assembly is simple in its construction and arrangement and can be readily lowered into and removed from the well bore in the form shown in Fig. 3.

Figs. 4 and 5 show an arrangement wherein the invention has been applied to a conventional pump plunger for wells. This plunger includes a body 40 having a threaded connection 41 to which the sucker rods in the well can be connected. This plunger has a travelling valve 42 arranged in the cage 43 at the upper end and has the openings 44 in the bottom so that on the down stroke liquid trapped in the working barrel or housing will be forced in the openings 44 upwardly through the hollow body portion 40 and discharged from the windows 45 above the travelling valve. On the up stroke the travelling valve will close and create a suction below the plunger in order to draw in a new charge of fluid.

This operation is, of course, dependent upon the providing of a seal about the plunger 40 and with the working barrel in the well. To accomplish this the sealing member 46 has been positioned over the central body portion of the plunger 40 so as to present the plurality of outstanding corrugations or lips 47 to form a seal with the surface of the working barrel. These lips are inclined upwardly as were the lips 32 of Fig. 1 for the same purpose, namely, to provide a seal. These lips are formed by the annular depressions 48 in the periphery of the member 46 and the lips are maintained in the desired position and distortion of the body is prevented due to the rigid reinforcing sleeve 49 which has the perforations 50 therein so as to embed it in the rubber or resilient material of the member. The ends of this reinforcing member may be turned outwardly as at 51 to present a rigid supporting surface to clamp the member in position.

This plunger may be used in an ordinary working barrel in a well without changing any of the standard construction of the well pump.

Figs. 6 and 7 show the invention as applied to a pump which may be of the type used in circulating the drilling mud or slush in the rotary method of drilling wells.

In this construction the pump body 60 is provided with a shoulder 61 and the annular supporting surface 62 so as to receive a metal liner 63. The pumping operation is accomplished by reciprocating the piston 64 by means of the piston or pumping rod 65 in the liner, it being understood that the pump embodies suitable controlling valves.

In the usual type of slush pump the liner 63 presents a smooth metal surface to the piston 64, but a great deal of wear occurs due to the abrasive materials in the slush being pumped. The present invention, therefore, contemplates that a sealing member or liner 67 can be inserted in the cut out portion 68 in the liner 63 and such member can be clamped in position by the retainer ring 69. This sealing member 67 is to some extent similar to those previously described and includes a cylindrical body 70 having the reinforced sleeve 71 therein. The periphery of this body 70 is formed with a plurality of annular corrugations or lips 73 which project inwardly in the form shown in Fig. 6. The crests 74 of these corrugations are arranged to provide a seal with the periphery of the pump 64 so that as the pump reciprocates a seal will be maintained by the plurality of lips or corrugations in contact therewith. The resilient nature of these lips prevents excessive wear thereon and it seems obvious that a pump equipped with the liner just described will provide a construction wherein a maximum of service will be obtained.

Broadly the invention contemplates a sealing member for pump plungers, pistons, liners and working barrels wherein a seal is maintained by the provision of resilient corrugations or lips upon either the moving or the stationary member of the pumping assembly.

What is claimed is:

45 A pump including a liner, means to seat the liner in the pump, said liner including a rigid hollow metal cylinder, an internal shoulder, a sealing cylinder disposed in said liner and having one end abutting said shoulder, a member 50 connected to said liner and affixing said sealing cylinder in said liner, said cylinder being of resilient material having a reinforcing sleeve imbedded therein, and symmetrical rounded corrugations internally thereof.

SAMUEL GORDON COLBAUGH.
